[57] **CLAIM**

The ornamental design for a combined helmet, head and cervical spine immobilizer, as shown and described.

DESCRIPTION

FIG. 1 is a perspective view of a combined helmet, head and cervical spine immobilizer, showing my new design; the broken line showing is for illustrative purposes only and forms no part of the claimed design;

FIG. 2 is a top plan view of a single combined helmet, head and cervical spine immobilizer;

FIG. 3 is a front elevational view thereof;

FIG. 4 is a rear elevational view thereof;

FIG. 5 is a bottom plan view thereof; and,
FIG. 6 is a side elevational view thereof, the opposite side elevational view being identical thereto.
